TRAVEL LIMITING DEVICE

John H. Michael, West Allis, and Thomas G. A. Sillers, Wauwatosa, Wis., assignors to Allis-Chalmers Manufacturing Company, Milwaukee, Wis., a corporation of Delaware

Application May 7, 1941, Serial No. 392,230

10 Claims. (Cl. 292—263)

This invention relates generally to travel limiting devices, and more particularly to devices for variably limiting the extent of the swinging movements of panel doors from and towards their closed and open positions.

In structures employing a plurality of hinged vertically mounted and aligned sections or panel doors, including such, for example, as electric switchboards and metal enclosed switchgear, it is the usual practice to mount on such doors, for metering and control, certain equipment, including such, for example, as electric meters and control switches. In order to permit access to the rear of such structures the extent of the outward swinging movement of the doors must be unduly limited, or the doors must be appreciably spaced in order to prevent damage by collision between the protruding equipment mounted on an open and on a closed door, respectively. Clearly such structures are disadvantageous with respect to equipment mounted on the doors thereof, especially where available space is limited, as in certain industrial and other installations.

It is therefore, an object of the present invention to provide improved means for limiting the swinging movements of panel doors outward from their supporting frames, or casings, a predetermined extent sufficient to permit observation and inspection of equipment positioned in the rear of such doors, but not to such an extent as to permit collision of such doors with adjacent doors, or collision with equipment supported thereon, together with means for permitting further outward swinging movement of such doors from their supporting frames a predetermined extent sufficient to permit maintenance operations and the removal therethrough of equipment positioned in the rear of such doors.

A further object of the present invention is to provide improved means for limiting the swinging movements of doors outward from their supporting frames, or casings, a predetermined extent sufficient to permit observation and inspection of equipment positioned in the rear of such doors, together with means for permitting further swinging movement of such doors outward from their supporting frames a predetermined extent sufficient to permit maintenance operations and the removal therethrough of equipment positioned in the rear of such doors, and means for selectively preventing and for permitting the complete closing swinging movement of such doors.

A further object of the present invention is to provide improved means for selectively permitting the swinging movement of doors outward from their supporting frames to a predetermined position and for permitting further outward swinging movement thereof to a second predetermined position, and for preventing closing movement thereof from the second predetermined position.

10 A further object of the present invention is to provide improved means adjustable to a plurality of alternate positions to selectively limit thereat the outward swinging movement of a door to a plurality of predetermined positions, and to selectively limit the closing movement of the door to a predetermined position different from the plurality of predetermined outward swinging positions.

15 A further object of the present invention is to provide an improved toggle-like mechanism coupling a door to a supporting frame structure in such a manner as to control the extent of the swinging movement of the door outward from its supporting frame, together with an adjustable stop means cooperating with the toggle mechanism to selectively vary the extent of such swinging movement.

20 A further object of the present invention is to provide an improved toggle-like mechanism coupling a door to a supporting frame structure in such a manner as to control the extent of the outward and closing swinging movements of the door relative to its supporting frame structure, together with adjustable stop means cooperating with the toggle-like mechanism to selectively limit the swinging movements of the door to a plurality of different outward positions and to a predetermined closing position.

25 Objects and advantages other than those above 30 set forth will be apparent from the following description and claims when read in connection with the accompanying drawing illustrating two embodiments of the invention.

35 Fig. 1 is a top view of portions of three adjacent aligned frame structures and three associated panel doors shown in their closed, intermediate and fully opened positions, respectively, and illustrating door stop mechanism embodying this invention;

40 Fig. 2 is an enlarged top view of portions of the structure shown in Fig. 1;

45 Fig. 3 is a front view of portions of the structure of Fig. 1 with portions of the door panel removed for the purpose of better illustration of 50 the door stop mechanism;

Fig. 4 is a sectional view on line IV—IV, of Fig. 3 showing an end view of the door stop mechanism;

Fig. 5 is an enlarged top view of portions of the structure of Fig. 1 showing one of the door panels and the associated stop mechanism in an intermediate stop position;

Fig. 6 is an enlarged top view of portions of the structure of Fig. 1 showing one of the door panels and the associated stop mechanism in a fully opened stop position; and

Fig. 7 is an enlarged top view of a modified embodiment of the invention wherein the stop means is so positioned and dimensioned as to permit opening movement of the door to a greater extent than as illustrated in Fig. 6 and to prevent closing movement of the door from such greater open position.

Referring now more particularly to the drawing by characters of reference, the reference numerals 10, 10a and 10b indicate portions of three aligned frame structures which may, for example, constitute metal box-like cubicle enclosures for electrical apparatus, such as metal clad draw-out type switchgear. The frame portions 10, 10a, and 10b are preferably arranged in abutting position as by being bolted together and they are severally provided with closure panel doors 11, 11a and 11b of suitable material and dimensions supported on the respective frames, as by suitably positioned hinge pins 12, for swinging movement relative thereto.

As indicated in Fig. 1 of the drawing, there may be suitably mounted on the respective panel doors 11, 11a and 11b equipment of various types, including such, for example, as electric measuring instruments, control relays, etc., generally designated 13, 14. The front faces of such equipment may extend an appreciable distance outward from the front face of the doors, or they may be so mounted as to present their front faces substantially flush, in a practical sense, with the front face of the doors and to extend a considerable distance from the rear surface of the doors.

In order to prevent injury, by collision, to the front surfaces of the doors, or injury to equipment mounted thereon, the doors 11, 11a, 11b, are, in the elected herein illustrated embodiments of the invention, severally pivotally linked to the respective frame portions 10, 10a and 10b by toggle arrangements severally consisting of the rods 15, 16 pivotally connected together by any suitable means, such as pivot pins 17, and pivotally connected at their outer ends to the respective doors 11, 11a and 11b by means, such as pivot pins 18 severally affixed to the doors 11, 11a and 11b and extending through the toggle rods 15, and to the frame portions 10, 10a and 10b by means, such as pivot pins 19 severally extending through the toggle bars 16 and through supporting bar members 20 severally rigidly affixed at a predetermined position to the respective frame portions 10, 10a and 10b, by means such as screws 31. Also pivotally supported on each supporting bar member 20 and cooperating with the associated toggle mechanism is a cam-shaped stop bar 33 having two or more contact surfaces 34, 35, alternately adjustable, by movement of a manually actuated knurled headed pivot pin 36 rigidly affixed to the stop bar 33 and extending through the supporting bar member 20, to position to contact with the toggle rod 16 upon outward swinging movement of the door 11, or 11a, or 11b, as the case may be, to predetermined positions in dependence upon the adjusted position of the stop

bar 33. Thus with the toggle bars 15, 16 and the stop bars 33 connected as indicated in the drawing and with the contact surface 34 of the stop bar 33 adjusted to the position shown in Fig. 5 of the drawing, then upon outward movement of the door 11, for example, approximately ninety degrees from its closed position the toggle rod 16 will make such contact with the surface 34 of the stop bar 33 as to prevent further outward movement of the door 11, and thereby prevent contact of the door 11 with the front surface of the adjacent door 11a, or contact with such equipment as may be mounted on either door 11 or 11a. Alternately with the stop bar 33 associated with the door 11 adjusted to the position shown in Fig. 6 of the drawing and the adjacent door 11a swung to the position indicated in Figs. 1 and 5 of the drawing, the outward swinging movement of the door 11 may be extended to the position shown in Figs. 1 and 6 of the drawing, at which position the toggle rod 16 will make such contact with the surface 35 of the stop bar 33 as will prevent further outward swinging movement of the door 11. Such extended outward position of the door 11 and the then position of the door 11a will be such as to permit maintenance operations on equipment positioned at the rear of the door 11 without possibility of injury, by collision, to the door 11 and door 11a, or injury to equipment mounted thereon.

To assure the prevention of injury by collision of the front surface of the door 11a, or with equipment mounted thereon with the front surface of the door 11 upon a reopening of the latter door after its closure following its movement to the position indicated in Figs. 1 and 6 of the drawing, it is necessary that the stop bar 33 for the door 11 be restored to its normal position, as indicated in Figs. 1, 2, 3 and 5 of the drawing. Such restoration may be accomplished by rotating, by movement of the knurled headed pin 36, the bar 33 substantially one hundred and eighty degrees in a clockwise direction, and in order that such restoration be not neglected, means, such as a stop pin 37, is affixed to and projects downward from the top surface of the door 11 at such position thereon as to contact with the stop bar 33 during closing movement of the door 11 when the bar 33 is adjusted to the position indicated in Fig. 6 of the drawing. Such contact of the stop pin 37 with the stop bar 33 limits the closing movement of the door 11 to the position indicated in dotted lines in Fig. 6, and constitutes a visual signal that the stop bar 33 should be restored to its normal position, as indicated in Figs. 2, 3 and 5 of the drawing.

In certain cases it is, at least, desirable that unintended reclosure of the doors from their fully opened position—as indicated in Fig. 6 of the drawing—be prevented, in order to assure thereby non-interference with maintenance and other operations with respect to equipment positioned in the rear of the doors. In such cases the positioning and the contact surfaces of the stop bar 33 may be as indicated in Fig. 7 of the drawing, wherein a contact surface 38—in lieu of the surface 35—is so formed and positioned as to permit movement of the toggle mechanism beyond its dead center in counterclockwise direction. When so moved, the toggle link 16 will contact with surface 38 of the stop bar 33 and prevent thereby material clockwise closing movement of the door 11, or 11a, or 11b, as the case may be. To thereafter effect reclosure of the door it is necessary that the toggle mechanism be restored

beyond its dead center in the clockwise direction and the door swung towards its closed position. It will, of course, be understood that to effect the complete closure of the door it is necessary that the stop bar 33 be first restored from the position thereof indicated in Fig. 7 of the drawing to its normal position, as indicated in Figs. 2, 3 and 5 of the drawing.

While the constructions disclosed herein are provided for the purpose of illustrating preferred embodiments of the invention, it is to be understood that the invention is not to be so limited, and that changes and modifications, including such as will variably limit the swinging movement of the doors to a greater plurality of outward positions, may occur to one skilled in the art without departing from the spirit of the invention or from the scope of the annexed claims.

It is claimed and desired to secure by Letters Patent:

1. The combination with a frame structure, and a door swingable relative to said frame, of means for variably limiting the extent of swing of said door in one direction comprising an element connected to said frame and to said door, means adjustable to one position to stop said door at a predetermined position and adjustable to another position to stop said door at another predetermined position, and means for controlling the extent of swing of said door in another direction comprising means cooperating with the second said means when adjusted to the said other position to stop said door at a third predetermined position.

2. The combination with a frame structure, and a door positioned on said frame and swingable relative thereto, of means for variably limiting the extent of opening movement of said door comprising a toggle mechanism having a pair of pivotally connected links respectively pivotally connected to said frame and to said door, and a means so positioned on said frame and so adjustable to a plurality of positions as to be engaged therat by a link of said toggle mechanism during said opening movement of said door and as to retain its adjustment in all its positions regardless of the pressure exerted thereon by said link.

3. The combination with a frame structure, and a door positioned on said frame for swingable movements relative thereto, of means for variably limiting the said movements comprising an element connected to said frame and to said door, means supported on said frame and adjustable to one position to be engaged by the first said means during opening movement of said door to thereby limit such movement of the latter to a predetermined position and adjustable to another position to be engaged by the first said means during further opening movement of said door to thereby limit the opening movement of the latter to a further predetermined position, and means positioned on said door for engagement with the second said means, when the latter is adjusted to the said other position, during closing movement of said door, to thereby limit closing movement of said door to a predetermined position.

4. The combination with a frame, and a door swingable relative to said frame, of means for variably limiting the extent of swing of said door comprising a stop adjustable to two positions, one of which limits the opening of said door to a predetermined position and the other of which limits the opening of said door to a greater pre-

determined open position and prevents closing movement from the said greater predetermined open position, and means cooperating with said stop, when adjusted to the said other position 5 thereof, to limit the closing movement of said door to a predetermined position less than the complete closure of said door.

5. The combination of a frame member, a door member swingable relatively to said frame, and a stop for said door comprising a toggle mechanism having a pair of pivotally connected links respectively pivotally connected to said frame and to said door, and a cam pivotally mounted on one of said members for adjustment relatively thereto 10 and so positioned as to engage one of said links to stop said door when said door reaches a position determined by the adjustment of said cam.

6. The combination of a frame member, a door member swingable relatively to said frame, and stop means for said door comprising a toggle mechanism having a pair of pivotally connected links respectively pivotally connected to said frame and to said door, and a cam pivotally mounted on one of said members for adjustment relatively thereto 15 and so positioned as to engage one of said links to stop said door when said door reaches a predetermined position which is variable in dependence upon the adjustment of said cam, said cam being adjustable in such manner as to engage said one of said links only after passage of said toggle mechanism through a dead center to prevent reclosure of said door.

7. The combination of a frame member, a door member swingable relatively to said frame, and stop means for said door comprising a toggle mechanism having a pair of pivotally connected links respectively pivotally connected to said frame and to said door, a cam pivotally mounted on one of said members for adjustment relatively thereto 20 and so positioned as to engage one of said links to stop said door when said door reaches a predetermined position which is variable in dependence upon the adjustment of said cam, and a stop mounted on the other one of said members and so positioned as to engage said cam to stop said door when said cam is given a predetermined adjustment and said door is swung away from said predetermined position into another predetermined position.

8. The combination of a frame structure, a door swingable relatively to said frame structure, and stop means for said door comprising elements so mounted on said frame structure and on said door as to leave said door free to swing back and forth between two predetermined positions and to stop said door at said positions by engagement of one of said elements with another one of said elements, and means for adjusting said one of said elements to leave said door free to swing only between two other predetermined positions.

6. The combination of a frame structure, a door swingable relatively to said frame structure, and stop means for said door comprising elements so mounted on said frame structure and on said door as to leave said door free to swing back and forth between two predetermined open positions and to stop said door at said positions by engagement of one of said elements with another one of said elements, and means for adjusting said one of said elements to leave said door free to swing only between closed position and

a position intermediate said predetermined open positions.

10. The combination of a frame structure, a door swingable relatively to said frame structure, and stop means for said door comprising elements so mounted on said frame structure and on said door as to leave said door free to swing back and forth between closed position and a predetermined intermediate open position and to

stop said door at said intermediate open position by engagement of one of said elements with another one of said elements, and means for adjusting said one of said elements to limit the opening of said door to an extreme open position in such manner as to prevent closing movement of said door from said extreme open position.

JOHN H. MICHAEL.

THOMAS G. A. SILLERS.
